UNITED STATES PATENT OFFICE.

ADOLPH S. KLEIN, OF CLEVELAND, OHIO.

DESIGN FOR A DISPLAY-CASE.

45,342.

Specification for Design.

Patented Mar. 3, 1914.

Application filed December 15, 1913. Serial No. 806,932. Term of patent 7 years.

To all whom it may concern:

Be it known that I, ADOLPH S. KLEIN, a citizen of the United States of America, residing at Cleveland, in the county of Cuyahoga and State of Ohio, have invented a new, original, and ornamental Design for a Display-Case, of which the following is a specification, reference being had to the accompanying drawing, forming part thereof.

The figure is a perspective view of a display case showing my new design.

I claim:

The ornamental design for a display case as shown.

In testimony whereof, I sign the foregoing specification, in the presence of two witnesses.

ADOLPH S. KLEIN.
